CLAIM

The ornamental design for a travel bottle cap with twisting locking lid, as shown and described.

DESCRIPTION

FIG. 1 is a front perspective view showing our new design for a travel bottle cap with twisting locking lid with the lid portion shown in an unlocked and closed position,

FIG. 2 is a front view thereof,

FIG. 3 is a rear view thereof,

FIG. 4 is a top view thereof,

FIG. 5 is a bottom view thereof,

FIG. 6 is a left side view thereof,

FIG. 7 is a right side view thereof,

FIG. 8 is a front perspective view of the travel bottle cap with twisting locking lid of FIG. 1 shown with the lid portion in a locked and closed position; and,

FIG. 9 is a front perspective view of the travel bottle cap with twisting locking lid of FIG. 1 shown with the lid portion in an unlocked and open position.

The broken lines showing a bottle depict environment and form no part of the claimed design. All other broken lines depict portions of the travel bottle cap with twisting lock lid that form no part of the claimed design.

1 Claim, 8 Drawing Sheets
